UNITED STATES PATENT OFFICE.

BENJAMIN R. BRIERLY AND EDWARD H. WAUGH, OF SEATTLE, WASHINGTON, ASSIGNEES TO SMITH CANNERY MACHINES COMPANY, OF SEATTLE, WASHINGTON, A CORPORATION OF WASHINGTON.

FISH-CLEANING DEVICE.

1,244,168.

Specification of Letters Patent. Patented Oct. 23, 1917.

Application filed February 9, 1916. Serial No. 77,314.

To all whom it may concern:

Be it known that we, BENJAMIN R. BRIERLY and EDWARD H. WAUGH, citizens of the United States, and residents of the city of Seattle, county of King, State of Washington, have invented certain new and useful Improvements in Fish-Cleaning Devices, of which the following is a specification.

Our invention relates to apparatus for 10 cleaning fish, and particularly to an apparatus which is intended for cleaning the visceral cavity of the fish, after the same has been opened.

The object of our invention is to provide 15 a device which will more perfectly clean this visceral cavity, than the devices now in use.

Our invention comprises the novel parts and combinations of parts which will hereinafter be described, and then particularly pointed out in the claims.

In the accompanying drawings we have shown our device embodied in the form of construction which is now preferred by us. 25 Figure 1 is a side elevation of our device, certain parts of the frame upon which it is mounted being shown in section.

Fig. 2 is a transverse section through the supporting frame, and also one of the cleaning brushes being shown in section.

Fig. 3 is a plan view of the device shown independently of the supporting frame.

Figs. 4 and 5 are like plan views of the device, showing modifications in construction and adjustment.

Fig. 6 is a vertical section through one of the devices, taken upon its axis of rotation.

Fig. 7 is a face view of one of the cleaning disks, differing from those shown in the 40 other figures, in having a smooth periphery.

Fig. 8 is a section through the disk of Fig. 7.

Fig. 9 is an enlarged side view of the section of the cleaning disk, showing the character of corrugations, which we prefer to use, and their relationship as to the different sheets forming a brush.

Fig. 10 is a section through the same.

In a type of fish-cleaning machine, which 50 is brought into large use, the fish are caught and held by conveyers which carry the fish through a definite path, during which prog-

ress the fish are acted upon by various apparatus to clean them, and remove the undesirable parts. Our device is intended for 55 applying to a machine of this general character. As the apparatus for carrying the fish is hardly a part of our present invention, we have shown this only in a fragmentary way.

Figs. 1 and 2 show certain of these parts. These, in the type of machine illustrated 60 show a series of spears or pointed dogs 3, which are movable toward and from each other to engage and to release the fish.

These pointed dogs are placed in the pivot 65 axis of a chain of which links 5 are shown, and are automatically reciprocated to engage and to free the fish at the desired points. The general outline of a fish has 70 been indicated by dotted lines in Fig. 1.

Before the fish reaches the position where it is to be acted upon by the device which is the subject of our present invention, it has had the head and tail removed and the abdominal cavity slit, so as to open up the 75 visceral cavity from one end to the other.

Looking lengthwise of the path of travel of the fish, the relative position of these parts is herein shown in Fig. 6.

The cleaning apparatus as herein shown, 80 consists essentially of a disk having the outer zone thereof composed of flexible plates or disks, which are adapted to enter the abdominal slot in the fish, and to rub the entire inner surface of the visceral cavity. As herein shown this disk is composed of a series of plates 10, which are clamped together by plates 12 at each side thereon, and is secured upon a sleeve 13 which is 85 mounted for rotation upon a shaft 14. The shaft 14 has one end, which is removed at some distance from the disk, mounted so as to permit a slight pivotal movement of the shaft 14, carrying with it the disk 1.

The preferred manner of operating this disk consists in anchoring the pivot end of the shaft 14 in a sleeve 15, which is mounted upon a shaft 18, which extends parallel with the direction of travel of the fish, and providing the end of the sleeve 13 adjacent the shaft 18, with a bevel gear 16, which meshes with a companion bevel gear 17 secured to turn with shaft 18.

The shaft 18 is journaled by bracket arms 34, which depend from the main frame 4 of the machine.

We have shown two of these cleaning disks 1, placed one close after the other in the path of travel of the fish. One of these is driven from a shaft 18 on one side of the machine, and the other from a corresponding shaft on the other side of the machine. 10 The manner of driving these disks is, however, not the most essential feature of our invention.

The shaft 14 which does not rotate, projects from the end of the sleeve 13, and has a collar 19 secured thereto and forming a thrust bearing for the sleeve 13. Upon its projecting end it has secured a bracket which has two arms 2, which extend laterally and then upwardly to form a yoke. 20 These arms extend up to a point opposite the sides of the fish as they pass by.

To one of the arms 2 are secured a series of spring presser fingers 21, these being bowed inward or toward the fish so as to 25 bear against its side, and press it against the brushing disk 1. One end 26 of each of these spring bars is loose and has a support bearing against the other end 2 of the yoke.

The same member which carries the arms 30 2 has a third arm 20, which is provided with a hole through which passes an adjusting bolt 22, which bolt is supported from the frame as by having its upper end screwed into a threaded hole in the frame. 35 This bolt extends beneath the arm 20 a considerable distance, and has surrounding it a spring 25 which is supported by an adjusting nut 23, and bears against the under side of the arm 20 to yieldingly support it and 40 the disk 1. The upward movement of the arm 20 is limited by set nuts 24. By this means the upward pressure of the cleaning disk against the fish may be adjusted, and the disk is free to yield should an unusually 45 large fish be presented thereto.

The material which we now prefer to use 50 for the plates 10 of the cleaning disk is rubber, and this preferably of a pure grade, without anything in the nature of fabric to 55 make it rigid or rough in its surface. Such a disk has its operating parts, that is the outer or peripheral zone, flexible so that it may adjust itself laterally, or in any other manner desired to variations in the position or size of the fish.

We now prefer to form these plates or 60 disks 10 with their outer edges roughened or corrugated. In Figs. 1 and 9 is clearly shown a form of corrugating the edges of 65 these disks which we have found to give good results. These corrugations 11 may be made of great range in size, but preferably the corrugations would not be large or of sharp character. At the same time we have 70 found that cleaning disks of this kind, hav-

ing a true peripheral margin, as is shown in Fig. 7, will produce good results. We do not therefore, wish to be limited to the use of disks having corrugated edges.

In Figs. 1 to 3 the disks 1 have been shown 70 as mounted perpendicularly to the rotative shaft, and this shaft is so placed that the disk is in the plane which includes the axis of movement of the fish. In Fig. 4 we have shown a modification of this structure, in 75 which the disk 1 is placed so that its plane makes a slight angle with the axis of movement of the fish. In other words the brushing disk instead of lying true in the visceral cavity, is placed slightly cornerwise or at an 80 angle.

In Fig. 5 another modification is shown, in which the position of the rotative sleeve 14, is as shown in Figs. 1 to 3 but the disk 1 is placed a little bit off from perpendicular to 85 the plane, whereby when rotated it produces what might be called a wabbling movement, its outer surface as it contacts with the fish thus having a certain amount of lateral movement as well as the rotative movement. 90 These positions of the disk may be advantageous in certain cases, but ordinarily we believe the position shown in Figs. 1 to 3 will be found satisfactory.

In the preliminary work of cleaning fish, 95 that is the work which precedes the acting of these brushes, the contents of the visceral cavity have been loosened and in the main removed. There is however, a sac lying along the inner side of the back-bone of the 100 fish, in which the blood settles, and it is sometimes difficult to get this removed cleanly. Also the interior of the fish needs brushing out. We have found that the type of cleaning apparatus herein shown and described effectively brushes the inside of the fish, removing all small particles of offal which may not have been previously removed, and also cleans out the blood sac. 105

It is believed that the operation of this 110 device will be evident from the previous description, and does not here need enlarging upon.

What we claim as our invention is:

1. A rotative brush for use in cleaning 115 the interior cavities of fish and composed of a series of soft, pliable rubber disks, having a wide outer zone unconfined to permit free lateral flexure.

2. A rotative brush for use in cleaning 120 the visceral cavities of fish comprising a series of flexible disks, the diameters of successive disks increasing from the outer disk at each side toward the center disk and all disks having a wide outer zone which is free 125 to bend laterally.

3. A rotative brush for use in cleaning the 130 visceral cavities of fish comprising a series of flexible disks having their outer zones unrestrained laterally and forming a rela-

tively thin brush, the diameters of said disks gradually increasing from the outer disk to the center disk, the outer peripheral zone of said brush having a cross section adapted to fit closely within the base of said cavity.

4. A rotative brush for use in cleaning fish composed of a series of flexible plates secured together in their central parts and free to yield in wide peripheral zone and a yielding presser opposite the outer yielding zone of said disks.

5. A device for cleaning the visceral cavities of fish, comprising a rotative shaft mounted to swing upon a transverse axis, a disk secured to the swinging end of the shaft and having a flexible peripheral section, and a yielding support for the swinging end of the shaft.

6. A device for cleaning the visceral cavity of fish comprising a shaft having a pivotal support at one end, a yielding support for the other end, a sleeve rotatively mounted upon said shaft, and a disk fixed to the outer or swinging end of the sleeve and having an outer zone of flexible material.

7. A device for cleaning the visceral cavity of fish comprising a shaft having a pivotal support at one end, a spring supporting its other end, a sleeve mounted to turn upon the shaft, a cleaning disk secured upon the

outer end of the sleeve, a bracket fixed upon the outer end of the shaft, spring presser fingers carried by said bracket and adapted to engage the outer surface of the fish, and a spring supporting the bracket.

35

8. A device for cleaning the visceral cavity of fish comprising a shaft having a pivotal support at one end, a spring supporting its other end, a sleeve mounted to turn upon the shaft, a cleaning disk secured upon the outer end of the sleeve, a bracket fixed upon the outer end of the shaft, spring presser fingers carried by said bracket and adapted to engage the outer surface of the fish, a bolt passing through said bracket and having a fixed support, a spring carried by the bolt and supporting the bracket, and a bracket stop carried by said bolt.

40

9. A device for cleaning the visceral cavity of fish, comprising a rotative disk, a yielding support for the same permitting movement in substantially the plane of the disk, an arm carried by the support for said disk, and curved spring bars secured by one end to said arm and extending closely adjacent the side face of the disk.

45

Signed at Seattle, Washington, this 31st day of January, 1916.
